THERMAL CIRCUIT BREAKER

Calvin J. Werner, Dayton, Ohio, assignor to General Motors Corporation, Detroit, Mich., a corporation of Delaware

Application February 14, 1938, Serial No. 190,437

3 Claims. (Cl. 200—138)

This invention relates to thermal responsive switches and includes among its objects the provision of a switch of such construction that, in response to variations in temperature of a bimetallic strip, the switch contacts will be abruptly opened or closed by a rapid movement of the contacts so that sparking will be reduced to a minimum.

Further objects and advantages of the present invention will be apparent from the following description, reference being had to the accompanying drawings wherein a preferred embodiment of the present invention is clearly shown.

In the drawings:

Fig. 1 is a perspective view of a switch embodying the present invention, the switch being closed.

Fig. 2 is a longitudinal sectional view of the switch showing the contacts closed.

Fig. 3 is a view similar to Fig. 2, showing the contacts opened.

Fig. 4 is a chart illustrating the operation of the present switch.

Fig. 5 is a diagram of certain movable parts of the switch.

The switch comprises a nonconducting bracket or mounting base 20, supporting terminals 21 and 22 having squared shank portions 21a and 22a which fit into square holes in the plate 20. The bolt 21 passes through sleeves 23 and 24 and threadedly engages a nut 25. The sleeve 23 telescopically receives the sleeve 24. Between shoulders provided by the sleeves 23 and 24, are clamped a contact stop 26 of relatively stiff metal and a relatively flexible contact spring 27 made of suitable resilient and electrically conducting material, such as phosphorous bronze. The contact spring 27 has a center portion or hub 27a which is apertured to receive the sleeve 24 by which the hub 27a is clamped against the contact stop 26. From the hub 27a extends an ear 27b which is apertured to receive a button 26b which is deformed from the contact stop 26. In this way the spring 27 is prevented from turning with respect to the contact stop 26. The contact stop 26 is prevented from turning with respect to the plate 20 by providing the plate 20 with a notch 28a which receives a strip 26a integral with the stop. Obviously, tightening the nut 25 on the bolt 21 secures contact stop 26 and the contact spring 27 in the desired position.

Strip 27 carries a contact 28 having a portion 28a of larger diameter than the adjacent hole in the stop 26, which hole is larger in diameter than the portion 28b of contact 28; and the portion 28b is wider axially than the thickness of the

stop 26. The contact 28 has a rivet shank portion 28c which passes through the spring 27 and a washer 29 and which is riveted, as shown, to secure the contact 28 to the spring 27. That portion of spring 27 which carries the contact 28 is connected with the hub portion 27a of the spring by resilient arms 27c which are so biased that the spring 27 is urged downwardly against the stop 26, as shown in Fig. 3.

Contact 28 is positioned for engagement by a contact 29 attached to the free end of a bimetallic thermostat blade 30, the fixed end of which is clamped between sleeves 31 and 32 which surround the bolt 22 which receives a nut 33 by which, in cooperation with the bolt 22, the parts 30, 31 and 32 are clamped in the position shown. In order to prevent turning of the blade 30 with respect to the bolt 22 and hence to prevent shifting of the blade with respect to the plate 20, the blade is provided with a downwardly extending strip 30a received by notch 35 in the plate 20. This strip 30a may serve as a means for attaching a wire, if desired.

The contact 29 is biased toward the contact 28 by coiled tension spring 40 having one end anchored to a strap 41 which encircles the sleeve 31 and is received by groove 31a therein. The other end of the spring 40 engages the yoke 42a of a U-shaped wire link member 42, the branches 42b of which are each pivotally connected at 42c with an ear 30b integral with the blade 30.

Referring to Fig. 2 it will be noted that the action line of spring 40, referring to the imaginary line which joins the two points of spring anchorage, is substantially below the pivotal connection between the link 42 and the thermostat blade ears 30b. Therefore, in normal condition, the spring 40 of the switch operates to exert a substantial force approximately vertically as viewed in Fig. 2 so as to bias the contact 29 upwardly against the contact 28 with contact pressure sufficient to cause the portion 28a of the contact 28 to bear against the under surface of the contact stop 26 and to urge the spring 27 upwardly away from the stop 26.

As the temperature of the blade 30 increases above a certain base or room temperature due to increase of temperature of the immediate surrounding atmosphere, or due to the heating effect of an electric current flowing through the blade, the blade will tend to bend downwardly in opposition to the force exerted against it by the spring 40. When the temperature of the bimetal blade 30 has reached a predetermined switch opening temperature, the tendency of the blade to bend

downwardly overcomes the tendency of the spring to prevent it. Then the contact 29 actually begins to move downwardly. Once it begins to move it will continue to move more and more rapidly away from the contact 28 because the component of force exerted by the spring 40 against the bimetal 30 diminishes since the pivot 42c is moving toward the center line of action of the spring 40. This force component of spring 40 diminishes at a rate substantially greater than the rate of decrease of the force of reaction exerted by the bimetal strip against the spring 40. Therefore once the contact 29 starts to separate from the contact 28, separation takes place in a rapidly accelerating manner and, hence, abruptly in order that sparking between the contacts will be minimized.

As the contact 29 starts to move downwardly the contact 28 follows up for a short distance until the contact spring 27 engages the upper side of the contact stop 26. This slight amount of follow-up movement is sufficient to be sure that the contact 29 has started downwardly a sufficient distance to insure that it will move all the way downward to separate the contacts. Theoretically such follow-up movement is not required; but, as a practical matter owing to inaccuracies in manufacture and friction between the moving parts, a fluttering action might occur if separation of the contacts were to take place during the first small increment of the downward movement of contact 29.

Mention has been made of the fact that the upward component of the force exerted by the spring 40 against the end of the bimetal blade 30 diminishes at a greater rate than the rate of decrease of the reaction of the blade 30 against the spring 40. This phenomena can best be explained with reference to Figs. 4 and 5. Fig. 5 diagrammatically represents spring 40, blade 30 and link 42 in cooperative relation when the contacts are closed. In this figure the dot 31 represents the bushing 31 to which the spring 40 and the blade 30 are attached. Dot 42c in Fig. 5 represents the pivotal connection between the spring-loaded arm or link 42 and the blade 30. Dot 42d represents the pivotal connection between spring 40 and the spring-loaded arm 42. The chart shown in Fig. 4 is based on certain dimensions of the parts. For example, the blade 30 is regarded as a cantilever spring 1.583" long, the arm 42 is .375" long and the distance between the eyes of spring 40 is 1.956". Normally the spring eye indicated at point 42d is .040" from the plane of the dots 42c and 31 which diagrammatically represents the plane of the blade 30. Normally the dot 42c representing the pivotal connections 42c in Figs. 1, 2 and 3 is .032" from the line of action of spring 40.

In Fig. 4 the horizontal line X—X is the base or zero line of spring-loading. Line Y—Y is the zero or base line of toggle deflection. Zero distance horizontally from line Y—Y represents the condition when the pivot point 42c coincides with the center line of action of spring 40, that is, the toggle pivot is in neutral position. Measurements horizontally to the right of line Y—Y represent the distance from the toggle pivot below the line 40. Distance vertically above the line X—X represents the reaction of the bimetal blade 30 against the vertical component of the spring-loaded arm 42 due to stress in the bimetal blade. Distance vertically below the line X—X represents reaction of the bimetal blade against the contact 28 due to stress in the bimetal blade. Dis-

tance vertically above the line X—X also represents the upward component of the spring-loaded arm 42 against the bimetal blade 30.

In Fig. 4 line a—a' is the load-deflection curve of the bimetal blade 30 at room temperature which, for example, may be around 100° F. Line b—b' is the load-deflection curve of the blade 30 at reset temperature which may be, for example, 167.5° F. Line c—c' is the load-deflection curve of the blade 30 at trip temperature, which may be, for example, at 201° F. Line c—e shows the load-deflection characteristic of the vertical component exerted upon the blade 30 by the spring-loaded arm 42. When the contacts are closed and the blade is at room temperature, the effective reaction exerted by the blade 30 against the toggle pivot 42c is zero, as represented by the point a. The deflection of point a from the toggle neutral is .033", which agrees with the dimensions shown in Fig. 5. The reaction of the vertical component to the spring-loaded arm 42 against blade 30 is represented by point c which is 3.41 ounces. This represents the contact pressure exerted upwardly by contact 29 against contact 28 when the switch is in the position shown in Fig. 2.

As the temperature of the bimetal blade 30 increases there is progressively built up in it a force opposing the reaction of the spring-loaded arm 42 which will cause downward movement of the pivot 42c to take place when the bimetal reaction downwardly becomes greater than the reaction of the spring-loaded arm upwardly. The characteristic of bimetal blade 30 at trip temperature is represented by line c—c' which intersects the line C—E at point C. At trip temperature the downward force of the bimetal blade slightly exceeds 3.41 ounces, thereby causing the contact 29 to begin to separate from the contact 28. As this separation takes place the downward reaction of the bimetal blade against the pivot 42c diminishes according to the line c—f while the upward component of the force exerted by the spring 40 on pivot 42c diminishes along the line c—e, which has a steeper slope than the line c—f, thereby denoting that the vertical component of the force exerted by spring 40 diminishes at a more rapid rate than the force exerted by the bimetal. Therefore, once the contact 29 begins to move downwardly from the position shown in Fig. 2 to that shown in Fig. 3, the force differential increases from zero at point C to a value represented by line f—e, when movement stops due to the fact that the rivet button 29a on the lower side of the blade 30 touches the upper side of the spring 40. When the button 29a is in its lowermost position as indicated by point f, the link pivot 42c will be .015" above the line of action of spring 40. The line f—e represents the trip line or the "off" position of the switch. After the switch has tripped open the value of f which is the force exerted by the blade 30, is 2.75 ounces and the upward force exerted by the spring-loaded arm 42 represented by e is 1.60 ounces. Therefore it is apparent that the force differential between the bimetal blade 30 and the spring-loaded arm 42 has increased from zero to 1.15 ounces during the tripping of the switch.

When the blade cools to a temperature slightly below that of 201° F. at which temperature the bimetal has the characteristic represented by line b—b', the switch will automatically close or reset and the closing of the switch will also take place by a snap action. This is due to the fact that, as the point 42c starts to ascend from the action

line of spring 40, that is, to increase its distance from 0.15" to the maximum which is .033", the vertical component of the force exerted by the spring 40 upon the bimetal blade 30 as represented by line e—c increases at a rate substantially greater than the rate of increase of the reaction of the bimetal blade against the arm 42 as represented by the line e—b.

From the foregoing description of the construction and mode of operation of the temperature responsive snap switch it is apparent that the switch comprises a bimetal blade and a control spring in opposing relation and connected with each other by means of a link or spring-loaded arm, the relation of these parts being such that separation of the switch contacts is accompanied by a decrease in the bias of the spring with respect to the bimetal blade, said bias decreasing at a rate greater than the rate of decrease of the reaction of the bimetal blade on the spring whereby the contacts are opened with an accelerated movement. It is also true that the relation between the parts is such that the approach of one contact toward the other is accompanied by an increase in bias of the control spring with respect to the bimetal blade, said increase taking place at a rate greater than the rate of increase of the reaction of the blade against the spring-loaded arm whereby the reengagement of the contacts takes place at an accelerated rate. Therefore when once the contacts begin to separate, they will separate with a quick, abrupt motion and also when the contacts begin to move one toward the other, the movement is relatively rapid. Consequently, the switch operates with an abrupt or snap action, tending to minimize sparking at the contacts.

While the embodiment of the present invention constitutes a preferred form, it is to be understood that other forms might be adopted, all coming within the scope of the claims which follow.

What is claimed is as follows:

1. A switch comprising in combination, a base,

a stationary contact secured to the base; a bimetallic thermal responsive element anchored at one end and having the other end adapted to flex in response to a temperature change; a cooperating contact secured to the thermal responsive element in alignment for engagement with the first-mentioned contact; a tension spring anchored at one end; a link member pivotally connected to the thermal responsive element and having the other end of the tension spring connected thereto; said tension spring, link and thermal responsive element being so relatively angularly disposed that a component of the force of said tension spring biases the contacts toward engagement by an amount which diminishes as the contacts move away from engagement; and stop means for preventing the said bias from passing through a zero value.

2. A switch comprising, in combination, a base, a stationary contact secured to the base; a bimetallic thermal responsive element anchored at one end and having the other end adapted to flex in response to a temperature change; a cooperating contact secured to the thermal responsive element in alignment for engagement with the first-mentioned contact; a tension spring having one end anchored near the anchored end of the thermal responsive element and extending beyond the free end of the thermal responsive element; means pivotally engaging the thermal element and angularly disposed with respect to the axis of the spring and the thermal responsive element for transmitting a component of the force of the spring to the thermal responsive element to normally bias the thermal responsive element in one direction; and stop means for preventing said means from crossing the axis of the spring.

3. A switch according to claim 1 in which the stationary contact is yieldably mounted so as to move with the contact on the thermal element as the latter moves in a direction to separate the contacts, and in which a stop limits movement of the yieldably mounted contact in this direction.

CALVIN J. WERNER.
